UNITED STATES PATENT OFFICE.

FRANCIS J. McLOUGHLIN, OF BROOKLYN, NEW YORK.

ONE-WAY EXIT GATE.

Application filed April 22, 1920. Serial No. 375,713.

To all whom it may concern:

Be it known that I, FRANCIS J. McLOUGHLIN, a citizen of the United States, residing in Brooklyn, county of Kings, the State of New York, have invented a certain Improvement in One-Way Exit Gates, of which the following is a specification.

At fair grounds, places of public amusement, railway stations, and similar localities it is desirable to provide means for convenient exit, so constructed as to prevent unauthorized admittance of the public, while making egress as easy as possible, particularly in rush hours.

For this purpose it has been customary, in many places, to provide turn-stiles so constructed as to yield to pressure in one direction only, and so constructed as to prevent entrance on the inwardly moving side of the revolving structure.

One disadvantage of this form of gate is that it must be made necessarily at least twice as wide as the space available for exit, thereby involving a great waste of space. Another objection is that the movable structure is heavy to move and makes a great deal of noise when used, particularly when a crowd is passing through. Again, if a person using the gate is carrying bags or bundles, the horizontal grating set at right angles forms a confining space which often occasions inconvenience, and the bars sometimes catch in the clothing or the bundles of the person passing through.

Turnstiles of this kind are expensive to build and the mechanism is subjected to continual wear and tear, necessitating repairs and consequent interruption of traffic.

The present invention relates to a relatively simple and inexpensive structure, entailing almost no waste of space, and by the use of which all of the above named disadvantages of the usual turnstile may be obviated.

Certain preferred forms of the invention are illustrated in the accompanying drawings, wherein Figure 1 is a diagrammatic plan view of a two-door straightaway form of the improved gate, Figure 2 is a similar view of a two-door gate presenting a right angled turn, and Figure 3 is a similar view of a two-door gate presenting a reverse turn.

In its simplest form the invention comprises a door 10 made just wide enough to allow one person to pass at a time, and adapted to be opened only from the inside

and by a movement outward only, as shown by the dotted line at each door. Such a door is combined with enclosing walls or fences 11, 12, forming a passage on the outside just wide enough for one person, and sufficiently long to prevent anyone reaching in from the outer end of such passage to hold the door open.

The door is arranged to close automatically in any well known manner, as by the use of a closing spring 13, or equivalent means. If the movable edge of the door is made to close flush with the wall or jamb so that it cannot be pulled open from the outside, this will suffice, but it is preferable to have a latch 14 of some kind on the inside so arranged that it cannot be operated from the outside of the door.

It will be clear from this description that any person passing outward through the door 10, as indicated by the arrow, must leave the passage between the walls 11 and 12 before an outsider can enter, and, by that time, the door will have been closed automatically, preventing entrance.

The only possibility of defeating the end in view, with the combination thus far described, would be found in collusive action. That is to say one person within might open the door for another who had come inward toward it, thus admitting the latter.

In order to prevent this, it is preferred to embody the invention in the two-door form shown in three arrangements in the drawings.

In this form, the walls 11 and 12 are prolonged to a second door 15, similar to the door 10, and preferably provided with a closing device 16 and an interior latch 17. Walls 18 and 19 may or may not be used outside of the second door 15, to form a narrow passage as shown.

In Figure 1 the door 15 is parallel to the door 10; but if desired the second door may be at right angles as at 20, in Figure 2, or at any other angle to the door 10.

In Figure 3, is shown a form in which the narrow passage outside of the first door makes a turn through two right angles, the second door 21 opening in the opposite direction from the door 10.

While it is preferred to arrange the door or doors to open outward, as shown, this is not essential to the invention, so long as they cannot be opened from the outside.

It will be seen that one of the advantages

of the invention is that, if desired, it can be used as an entrance, by merely fastening back all of the doors. In times of emergency this extra capability takes on considerable importance.

What I claim is—

1. A one-way exit comprising a self closing door adapted to be opened by the person passing through and from the inside only and a passage closed in on both sides to prevent entrance leading outward from said door so long as to prevent the door from being reached from the outer end of the passage substantially as described.
- 10 2. A one-way exit comprising a self closing door adapted to be opened by the person

passing through and from the inside only, a narrow passage closed in on both sides to prevent entrance to the passage leading outward from said door, and a second self closing door on the outer end of said passage.

3. A one-way exit comprising a long narrow passage closed in on both sides to prevent entrance and just wide enough for one person, a self closing door at the inner end 25 of said passage adapted to be opened by the person passing through from the inside only and a second self closing door at an intermediate point in said passage.

In testimony whereof I have hereto set 30 my hand on this 19th day of April, 1920.

FRANCIS J. McLOUGHLIN.
